UNITED STATES PATENT OFFICE

1,949,747

WARP STOP MOTION

John Jacob Kaufmann, Elkins Park, Pa., assignor
to Steel Heddle Manufacturing Company, Phila-
delphia, Pa., a corporation of Pennsylvania

Application January 20, 1932, Serial No. 587,655

12 Claims. (Cl. 139—355)

My invention relates to warp stop motions for looms, and relates more particularly to improved means, in a loom harness frame, for establishing an electrical circuit whenever a warp end breaks or becomes unduly slack, whereby the loom may be automatically stopped by means of electrical devices included in or controlled by said circuit.

The principal object of my invention is to provide improved means, in a loom harness frame, for closing an electrical circuit whenever 10 a warp end breaks or becomes unduly slack.

With the foregoing object in view, my invention contemplates the utilization of a novel form of heddle preferably made of thin, flat metal or wire, which may be expeditiously and inexpensively made by means of the machinery at present in use for making the well known "steel heddles", which are now extensively used in loom harness.

20 My invention further contemplates the provision of a device of the character aforesaid, in which wear on the contacting elements will be reduced to a minimum.

My invention further contemplates the provision, in such a device, of contact making devices 25 which may be located entirely above the shed, to the end that the same will be readily accessible and will not become fouled by the lint which is disengaged from the warp ends during the manipulation thereof to form the successive sheds.

The nature and characteristic features of my invention will be more readily understood from the following description, taken in connection with the accompanying drawings forming part 30 hereof, in which:

Figure 1 is a front elevation of a loom harness frame, having mounted therein devices embodying the main features of my present invention; 40 Fig. 2 is an enlarged section thereof, taken on the line 2—2 of Fig. 1;

Fig. 3 is an enlarged section, taken on the line 3—3 of Fig. 1, showing a portion of a heddle, and illustrating the relative locations, when the harness frame is in the elevated position, of the 45 upper supporting rod and an auxiliary contact bar by means of which the electrical circuit is established when a warp end is broken or slack.

Fig. 4 is a similar view, illustrating the relative locations of said members when the harness frame is in the lowered position;

Fig. 5 is a similar view, illustrating the relative locations of said members when the harness frame is in the lowered position, and the 55 warp end controlled by the heddle there shown

is broken or slack, permitting the heddle to drop to the contact making position; and

Fig. 6 is an enlarged section, taken on the line 6—6 of Fig. 1, illustrating the lower portion of one of the heddles.

It will, of course, be understood that the description and drawings herein contained are illustrative merely, and that various changes and modifications may be made in the structure disclosed without departing from the spirit of the 60 invention.

The heddle frame may be of any preferred construction. As shown in the drawings, it may comprise top and bottom rails 10 and 11, respectively, preferably made of wood, and connected at their ends by struts 12 and 13, preferably made of metal. Heddle supporting rods 14 and 15 are mounted in the end struts in the customary manner.

An auxiliary contact bar is also mounted in 75 the end struts 12 and 13. The contact bar comprises a central metallic strip 17, partially surrounded by insulation 18, which in turn is partially surrounded by a metal sheathing 19, U-shaped in cross-section.

The ends of the contact bar extend through elongated slots 20 in the end struts 12 and 13, so that said contact bar may be permitted a rising and falling movement with respect to the heddle supporting rods, in the manner and for 80 the purpose to be hereinafter set forth.

The contact bar is preferably positioned in the frame above the upper supporting rod 14, but, of course, it will be understood that the same may be located in any other suitable portion of the 85 harness frame, if desired.

The external metallic sheathing 19 of the contact bar is in electrical connection with the metal struts 12 and 13 of the frame, where said contact bar extends through the slots in said struts, but in order to insure a positive electrical connection, a wire 21 may be employed, being secured at one end to the metal sheathing 19 by a screw 22, and at the other end to the side strut 13 of the frame, by a screw 23.

The screw 23 may also, if desired, be used as a means of connecting a wire 24, forming part of the electrical circuit to be controlled.

One end of the central metallic strip 17 may extend beyond the end of the sheathing 19, and current may be supplied thereto by means of a wire 25, one end of which is secured by a screw 26 to the protruding end of the strip 17, and the other end of which is secured by a screw 27 to an insulating block 28. The screw 27 may also be 110

used for the connection of a wire 29, which forms part of the electrical circuit to be controlled.

Each of the heddles 30 is preferably made of a thin, flat strip of metal or wire, having a central warp eye 31 of the type usually provided therein, and elongated slots 32 and 33, near the ends thereof, for mounting the same on the supporting rods 14 and 15, respectively. The slots 32 and 33 are of a length greater than the width of the supporting rods 14 and 15, so that the heddles will have a range of vertical movement with respect to said supporting rods, as the harness frame is raised and lowered, this movement being imparted to the heddles by the tension of the warp ends as the shed is formed.

Each of the heddles 30 is also provided, at its upper end, adjacent the slot 32, with an auxiliary slot 34, through which the contact bar extends. The slot 34 is likewise of a greater length than the overall width of the contact bar, but the excess of length thereof is somewhat less than the excess of the length of the slots 32 and 33, through which the supporting rods 14 and 15 extend.

The slot 34 is so positioned with respect to the slot 32 that when the harness frame is in the raised position, and the heddles are resting with the upper ends of the slots 32 on the top edges of the supporting rod 14, the contact bar will be positioned in the slot 34 of each heddle with the top end of the slot 34 free of engagement with the central metallic strip 17 of the contact bar. The top marginal edge of the slot 34 is preferably inclined, as at 35, for a purpose to be presently explained.

The operation of the device may now be explained. When the harness frame is in the elevated position, the heddles fall by gravity, and also by the reason of the tension imparted thereto by the warp ends, to the position shown in Fig. 3 of the drawings, being supported by the upper ends of the slots 32 resting upon the top edge of the supporting rod 14. The contact bar 16 also falls by gravity to the position shown in Fig. 3 of the drawings, being so located by reason of its resting at the bottom of the slots 20 in the end struts 12 and 13 of the frame.

When, however, the harness frame is lowered, the tension imparted by the warp threads pushes the heddles upwardly with respect to the supporting rods, whereupon the lower edge of the contact bar will be engaged by the lower ends of the slots 34 of the heddles, and the contact bar will thereby be raised with respect to the supporting rod 14, as illustrated in Fig. 4 of the drawings, this raising being permitted by reason of the provision of the slots 20 in the end struts 12 and 13 of the frame.

Should, however, one of the warp ends break or become unduly slack, the heddle through which said warp end passes will be permitted to drop, whereupon the inclined upper edge 35 of the end of the slot 34 will engage the central metallic strip 17 of the contact bar, sliding over the same until the side margin of the slot 34 engages the metallic sheathing 19 of the contact bar.

At this stage of the operation, current being supplied to the central strip 17 of contact bar through the wires 29 and 25, the same will pass through the heddle which has fallen, from the metallic strip 17 to the outer metallic sheathing 19, and thence by wires 21 and 24. In this manner, the circuit will be established for the actuation of any of the well known electrical devices for stopping the loom, not shown.

Inasmuch as the screw 23 is mounted directly

in the metallic end strut 13 of the frame, it will be apparent that if the circuit is not established through the metal sheathing 19, as the current passes to a dropped heddle from the central strip 17, there will be an alternative electrical path provided through the heddles, thence through one or the other of the heddle supporting rods 14 and 15, to the side strut 13 in which the screw 23 is mounted.

It will, of course, be understood that the individual harness frames may, if desired, be provided with means (not shown) for supplying current to the contact bar at such times only as the harness frames are in the lowered positions. It is not deemed necessary to show such devices, as the same are well known, and may assume a variety of forms.

It will be noted that the contact making portion of each heddle is kept out of contact with the central strip 17 of the contact bar, except when an individual heddle drops by reason of a broken or slack warp end, and consequently wear of the contact bar and the coacting portions of the heddles is reduced to a minimum. The strain imparted to the heddles when the shed is formed is taken up entirely by the supporting rods 14 and 15.

Furthermore, the contact making parts are arranged above the shed, and are at all times freely accessible. These parts will thus be maintained substantially free of the lint which falls from the warp ends when the same are manipulated in the forming of the successive sheds.

While the heddles may of course be made in any desired manner, preferably they may be inexpensively made by means of the machines now used for the making of heddles from a thin, flat strip of metal or wire.

I claim:

1. In a loom harness, a harness frame; warp shedding heddles; means for supporting said heddles in the frame; a contact bar mounted in the frame so as to have a range of vertical movement with respect thereto and adapted to be moved to its operative position when the frame is lowered; each of said heddles having a slot through which the contact bar extends, said slot being independent of the means for supporting the heddle in the frame, the upper end of said slot being normally free of engagement with the contact bar but adapted to engage the same to establish an electrical circuit when the warp end controlled by the heddle is broken or unduly slack.

2. In a loom harness, a harness frame; warp shedding heddles; means for supporting said heddles in the frame; a contact bar mounted in the frame so as to have a range of vertical movement with respect thereto and adapted to be moved to its operative position when the frame is lowered; each of said heddles having a slot at the upper end thereof through which the contact bar extends, said slot being independent of the means for supporting the heddle in the frame, the upper end of said slot being normally free of engagement with the contact bar but adapted to engage the same to establish an electrical circuit when the warp end controlled by the heddle is broken or unduly slack.

3. In a loom harness, a harness frame; warp shedding heddles; means for supporting said heddles in the frame; a contact bar comprising a central metallic strip and external metallic sheathing, said strip and sheathing being insulated from each other throughout their length,

- the upper edge of the central metallic strip protruding above the edge of the metallic sheathing, said contact bar being mounted in the frame so as to have a range of vertical movement with respect thereto and being adapted to be moved to its operative position when the frame is lowered; each of said heddles having a slot at the upper end thereof through which the contact bar extends, said slot being independent of the means for supporting the heddle in the frame, the upper end of said slot being normally free of engagement with the contact bar but adapted to engage the central metallic portion thereof to establish an electrical circuit when the warp end controlled by the heddle is broken or unduly slack.
4. In a loom harness, a harness frame; warp shedding heddles; means for supporting said heddles in the frame; a contact bar comprising a central metallic strip and external metallic sheathing, said strip and sheathing being insulated from each other throughout their length, the upper edge of the central metallic strip protruding above the edge of the metallic sheathing, said contact bar being mounted in the frame so as to have a range of vertical movement with respect thereto and being adapted to be moved to its operative position when the frame is lowered; each of said heddles having a slot at the upper end thereof through which the contact bar extends, said slot being independent of the means for supporting the heddle in the frame, the upper end of said slot being inclined and normally free of engagement with the contact bar but adapted to engage the central metallic portion thereof to establish an electrical circuit when the warp end controlled by the heddle is broken or unduly slack.
5. In a loom harness, a harness frame; warp shedding heddles mounted therein; means for supporting said heddles whereby the same have a range of vertical movement with respect to the frame; a contact bar mounted in the frame so as to have a range of vertical movement with respect thereto and being adapted to be moved by the heddles to its operative position when the frame is lowered; each of said heddles having a slot through which the contact bar extends, said slot being independent of the means for supporting the heddle in the frame, the upper end of said slot being normally free of engagement with the contact bar but adapted to engage the same to establish an electrical circuit when the warp end controlled by the heddle is broken or unduly slack.
6. In a loom harness, a harness frame; warp shedding heddles mounted therein; means for supporting said heddles whereby the same have a range of vertical movement with respect to the frame; a contact bar mounted in the frame so as to have a range of vertical movement with respect thereto and being adapted to be moved by the heddles to its operative position when the frame is lowered; each of said heddles having a slot at the upper end thereof through which the contact bar extends, said slot being independent of the means for supporting the heddle in the frame, the upper end of said slot being normally free of engagement with the contact bar but adapted to engage the same to establish an electrical circuit when the warp end controlled by the heddle is broken or unduly slack.
7. In a loom harness, a harness frame; upper and lower heddle supporting rods mounted therein; heddles mounted on said rods; a contact bar
- mounted in the frame so as to have a range of vertical movement with respect to the heddle supporting rods and being adapted to be moved by the heddles to its operative position when the frame is lowered; each of said heddles having a central warp eye and a slot adjacent each end thereof for mounting the same on the supporting rods, said slots being elongated whereby the heddle has a range of vertical movement with respect to the supporting rods, each of said heddles also having an additional slot through which the contact bar extends, the upper end of said slot being normally free of engagement with the contact bar but adapted to engage the same to establish an electrical circuit when the warp end controlled by the heddle is broken or unduly slack.
8. In a loom harness, a harness frame; upper and lower heddle supporting rods mounted therein; heddles mounted on said rods; a contact bar mounted in the frame so as to have a range of vertical movement with respect to the heddle supporting rods and being adapted to be moved by the heddle to its operative position when the frame is lowered; the heddles being made of thin flat metal or wire, each of said heddles having a central warp eye and a slot adjacent each end thereof for mounting the same on the supporting rods, said slots being elongated whereby the heddle has a range of vertical movement with respect to the supporting rods, each of said heddles also having an additional slot through which the contact bar extends, the upper end of said slot being normally free of engagement with the contact bar but adapted to engage the same to establish an electrical circuit when the warp end controlled by the heddle is broken or unduly slack.
9. In a loom harness, a harness frame; upper and lower heddle supporting rods mounted therein; heddles mounted on said rods; a contact bar mounted in the frame so as to have a range of vertical movement with respect to the heddle supporting rods and being adapted to be moved by the heddles to its operative position when the frame is lowered; the heddles being made of thin flat metal or wire, each of said heddles having a central warp eye and a slot adjacent each end thereof for mounting the same on the supporting rods, said slots being elongated whereby the heddle has a range of vertical movement with respect to the supporting rods, each of said heddles also having an additional slot at the upper end thereof, the contact bar extending through said slot, the upper end of said slot being normally free of engagement with the contact bar but adapted to engage the same to establish an electrical circuit when the warp end controlled by the heddle is broken or unduly slack.
10. In a loom harness, a harness frame; upper and lower heddle supporting rods mounted therein; heddles mounted on said rods; a contact bar comprising a central metallic strip and external metallic sheathing, said strip and sheathing being insulated from each other throughout their length, the upper edge of the central strip protruding above the upper edge of the metallic sheathing, said contact bar being mounted in the frame so as to have a range of vertical movement with respect to the heddle supporting rods and being adapted to be moved by the heddles to its operative position when the frame is lowered; the heddles being made of thin flat metal or wire, each of said heddles having a central warp eye and a slot adjacent each end thereof for mount-

ing the same on the supporting rods, said slots being elongated whereby the heddle has a range of vertical movement with respect to the supporting rods, each of said heddles also having 5 an additional slot through which the contact bar extends, the upper end of said slot being normally free of engagement with the contact bar but adapted to engage the central metallic portion thereof to establish an electrical circuit when 10 the warp end is broken or unduly slack.

11. In a loom harness, a harness frame; warp shedding heddles; means for supporting said heddles in the frame; a contact bar mounted in the upper portion of the frame so as to have 15 a range of vertical movement with respect thereto and adapted to be moved to its operative position when the frame is lowered; each of said heddles having a portion normally free of en-

gagement with the contact bar but adapted to contact therewith to establish an electrical circuit when the warp end controlled by the heddle is broken or unduly slack.

12. In a loom harness, a harness frame; upper and lower heddle supporting rods fixedly mounted therein; warp shedding heddles mounted on said rods; a contact bar mounted in the frame so as to have a range of vertical movement with respect thereto and adapted to be moved to its operative position when the frame is lowered; each of said heddles having a portion normally free of engagement with the contact bar but adapted to contact therewith to establish an electrical circuit when the warp end controlled by the heddle is broken or unduly slack. 80 85 90
